US0D1099960S

(12) **United States Design Patent** (10) **Patent No.:** **US D1,099,960 S**
(45) **Date of Patent:** **** Oct. 28, 2025**

(54) **DISPLAY SCREEN WITH GRAPHICAL USER INTERFACE**

(71) Applicant: **The PNC Financial Services Group, Inc.**, Pittsburgh, PA (US)

(72) Inventors: **Peter Scott Bird**, Pittsburgh, PA (US); **Seth Storck**, Pittsburgh, PA (US); **Piita Garvey**, Pittsburgh, PA (US)

(73) Assignee: **THE PNC FINANCIAL SERVICES GROUP, INC.**, Pittsburgh, PA (US)

(**) Term: **15 Years**

(21) Appl. No.: **29/953,884**

(22) Filed: **Jul. 24, 2024**

Related U.S. Application Data

(63) Continuation of application No. 29/925,916, filed on Jan. 26, 2024.

(57) **CLAIM**

The ornamental design for a display screen with graphical user interface, as shown and described.

DESCRIPTION

The FIGURE is a front view of a display screen portion with graphical user interface showing the claimed design.

The exterior uneven-length broken lines illustrate a display screen and form no part of the claimed design. The remaining even-length broken lines illustrate portions of the graphical user interface and form no part of the claimed design.

1 Claim, 1 Drawing Sheet
